LEROY C. DOANE, OF MERIDEN, CONNECTICUT, ASSIGNOR TO THE MILLER COMPANY, OF MERIDEN, CONNECTICUT, A CORPORATION OF CONNECTICUT

INCLOSED LIGHTING FIXTURE

Application filed July 20, 1927. Serial No. 207,086.

The present invention relates to an inclosed lighting fixture and is more particularly directed toward an inclosed lighting fixture suitable for use in lighting automotive vehicles such as busses.

The present invention contemplates an inclosed lighting unit for the above purpose having a glass bowl or globe preferably made of diffusing glass, a metallic globe holder and a cooperative shade support adapted to be carried by the bus ceiling or other supporting structure. The lamp socket is permanently supported by the shade holder and the shade holder, is, according to the present invention, provided with an arrangement of lugs adapted to cooperate with a suitable shade supporting ring so that the shade with ring attached to it may be quickly and easily mounted in the shade support.

An object of the present invention is to provide a metal supporting ring which is non-rotatably carried by the glass shade in such a way that the ring and shade may be handled as a unit in attaching the unit to the supporting shade holder.

Another object of the invention is to provide a small inclosed shade of diffusing glassware of such shape that light may be directed onto the bus ceiling and upper side walls as well as downwardly.

Other and further objects of the invention will appear as the description proceeds.

The accompanying drawings show, for purposes of illustration, one of the many possible embodiments in which the present invention may take form, it being understood that the drawings are illustrative of the invention rather than limiting the same.

In these drawings:

Figure 1 is a sectional view of an inclosed lighting unit, parts being shown in elevation;

Figure 2 is a top plan view of the shade or globe and shade holding ring, parts being shown in section approximately on the line 2—2 of Figure 1; and

Figure 3 is a perspective view of two stampings forming the shade holding ring.

A support, such as the ceiling of a bus, is indicated at 10. A metal shade support 11 is mounted in a suitable hole or opening in a

bus ceiling being supported in place by screws 12. A lamp socket 13 of the type ordinarily used in automotive electrical equipment is supported in the shade support 11 by means of a strap 14 which is fastened to the shade support by screws 15. These screws also support arcuate springs 16 and 17. The shade support 11 is open from underneath and the interior of the shade support is provided at the lower end with sloping shoulders indicated in dotted lines at 18 and with suitable recesses or dwells 19 to receive lugs carried on the shade holding ring.

A shade 20 preferably made of diffusing glass has, as here shown, a curved bottom 21, conical side walls 22 and inwardly flaring upper walls 23. The upper walls 23 terminate in a short tubular neck 24. This neck is approximately cylindrical but is, as here shown, provided with indentations 25, 26, 27 and 28.

An upper shade holder ring 29 is shown more in detail in Figure 2. The ring has four inwardly bent lugs or prongs 30, 31, 32 and 33 adapted to fit into the indentations 25, 26, 27 and 28 on the glass shade so as to prevent relative rotation of the shade and ring. The shade ring 29 is also provided with a downwardly directed internally threaded central portion 32' spaced sufficiently from the outer wall or skirt 33' so as to pass down inside the neck 24 of the glass shade. A locking ring 34 shown more in detail in Figure 4 is provided with an upwardly drawn threaded portion 35 adapted to cooperate with the threads 32' on the locking ring 29. The locking ring has cut away sides indicated at 36 and 37 to permit passing it downwardly through the opening in the glass shade. The flanges 38 and 39 of the locking ring are adapted to engage underneath the glass shade as indicated more clearly at the left of Figure 1. To facilitate assembling the two rings, the locking ring 34 is provided with a number of inwardly bent prongs 40 which may be engaged by a special tool so that the locking ring 34 may be turned relative to the cover ring 29 thereby threading the parts together and securely fastening the globe between two rings. The globe and two

rings then form a unit which may be mounted in the holder. The ring 27 is just the proper size to freely pass upwardly in the shade holder and it is provided with a number of outwardly directed lugs 41 which are cooperative with the shoulders 18 and recesses 19 in the shade holder to securely hold the shade in place, the lugs being pressed into the recess by the springs 16 and 17 above referred to.

This form of bus lighting unit is well suited with large size lamp bulbs and yet is capable of being mounted very close to the ceiling with the attendant advantages. By 15 making the shade out of diffusing glass soft even light is sent out in all directions and the ceiling and upper side walls of the bus are lighted instead of being dark. The shade may be readily removed for inspection, cleaning and replacement of lamps.

I claim:

1. An inclosed lighting unit comprising a glass globe closed at the bottom and having a neck at the upper end, a threaded ring 25 outwardly flanged at its lower end, the ring being insertable through the neck of the globe to bring the flange underneath a portion of the globe, a cover ring having an outer portion which passes down outside the neck of 30 the globe and a second threaded portion cooperative with the threaded ring for clamping the globe between the rings, the outer portion of the cover ring and the neck of the globe being non-circular to prevent relative 35 rotation.

2. An inclosed lighting unit comprising a glass globe closed at the bottom and having a neck at the upper end, a threaded ring 40 outwardly flanged at its lower end, the ring being insertable through the neck of the globe to bring the flange underneath a portion of the globe, a cover ring having an outer portion which passes down outside the neck of 45 the globe and a second threaded portion cooperative with the threaded ring for clamping the globe between the rings, the outer portion of the cover ring and the neck of the globe being non-circular to prevent relative rotation, the threaded portion of 50 the first mentioned ring having inwardly bent tool engaging prongs to facilitate threading the two rings together.

3. A glass globe for inclosed bus lights, comprising a substantially closed glass bowl 55 having a narrow neck or opening at the top, said neck having uniformly straight side walls and being of non-circular configuration.

4. A glass globe for inclosed bus lights comprising a substantially closed glass bowl 60 having a narrow neck or opening at the top, said neck having straight side walls, said side walls having pockets or recesses 65 extending in the direction of the axis of the globe for receiving prongs on a cover ring or the like.

5. A holder for inclosed globes, said holder comprising two rings threaded together, one ring having an outwardly extending flange at its lower end while the other ring has an outwardly extending flange at its upper end and a skirt extending downwardly from the flange, said skirt having inwardly struck prongs for non-rotatably engaging a shade. 70

6. A holder for inclosed globes, said holder comprising two rings threaded together, one ring having an outwardly extending flange at its lower end while the other ring has an outwardly extending flange at its upper end and a skirt extending downwardly from the flange, said skirt having inwardly struck prongs for non-rotatably 75 engaging a shade and outwardly struck prongs to engage a shade support. 80

7. A bus light comprising an automotive lamp socket, a lamp bulb in the socket, a shade support about the lamp socket, a glass shade closed at the bottom and having a narrow neck at the top, and a pair of metal shade holding rings threaded together and non-rotatably clamped to the neck of the glass shade so that the shade and rings become a permanent subassembly, the outer ring being cooperative with the shade support for removably carrying the shade from the shade support, the hole in the rings being slightly 90 larger than the bulb to permit removal of the shade and rings from the shade support. 95

Signed at Meriden, in the county of New Haven and State of Connecticut, this 16th day of July, 1927.
